UNITED STATES PATENT OFFICE

2,197,404

FLOOR CRAMP

Roy E. Chapman, Cincinnati, and John Cahall, Norwood, Ohio, assignors, by direct and mesne assignments, of one-half to Ivah Barkley, Norwood, Ohio, and one-half to said Cahall

Application August 9, 1939, Serial No. 289,250

7 Claims. (Cl. 254—12)

The invention relates to floor cramps for forcing the joints of floor boards close together prior to the boards being nailed. It is the object of our invention to provide an improved cramp which will be positive in its action, which will exert a very powerful cramping action and which will be easy to manipulate and to move about during use.

It is specifically the object of our invention to provide a floor cramp wherein a foot treadle exerts a direct leverage action on a gear segment which actuates a rack bar provided at its end with a cramping head.

It is a further object of our invention to provide a floor cramp wherein the force exerted against the edge of the floor boards is slightly downwardly so that any tendency for the application of pressure to result in the floor boards springing up is avoided.

It is a further object of our invention to provide a floor cramp wherein cleats for holding the apparatus in position on the underlying floor boards may be adjustable for various types of work.

Broadly it is the object of our invention to provide a floor cramp wherein great leverage may be obtained in an apparatus of simple and readily portable construction, which will greatly facilitate the work of a floor layer.

The above objects and other objects to which reference will be made in the ensuing disclosure, we accomplish by that certain combination and arrangement of parts of which we have illustrated a preferred example.

In the drawing:

Figure 1 is an end elevation of a preferred type of device, with a portion thereof shown in section, as indicated by the lines 1—1 in Fig. 2.

Fig. 2 is a sectional view taken along the lines 2—2 of Fig. 1.

Fig. 3 is a perspective view of the cramping head.

The tool is provided with a base plate 1 having threaded openings 2 therein, arranged at spaced intervals wherein cleats 3 having shanks 4 may be adjustably mounted by means of nuts 5. If it is desired to expand the cleats 3 further from the base plate 1, this may be accomplished by turning down the threaded shanks 4 and adjusting the nuts 5 in a different position.

A guide plate 6 is provided with a milled slot 7 which as shown in Fig. 2, is inclined downwardly toward the open end of the slot so that the rack bar 8 which has the cramping head 9 pivotally secured thereto as indicated at 10, will have a

movement slightly downwardly from horizontal, so that the tendency to cause the floor board to buckle when pressure is applied, is avoided.

A housing 11 has a boss 12 with a trunnion bearing 13 for the foot pressure lever 14. The lever 14 has a foot rest plate 15, pivoted thereto as indicated at 16.

Journalized on the lever 14 at 17 we employ a link 18 which is journalized as indicated at 19 to a gear segment 20. The teeth 21 of the gear 10 segment engage the teeth 22 of the rack bar 8.

Thus it will be obvious that downward pressure on the foot plate of the lever 14 causes the gear segment 20 to rotate clockwise as indicated in Fig. 2, and this causes the rack bar 8 to be advanced to the left as shown in this figure, so that the cramping head 9 will compress the floor board in proper position for nailing.

A boss 23 is extended from the link 18 and a rod 24 extends from the boss 23, so that a spring 25 which has its lower end bearing against a shoulder 26 in the housing 11, will be compressed during the actuation of the machine by means of the lever 14.

A pawl 27 engages a ratchet segment 28 formed in the periphery of the gear segment 20 opposite the gear teeth 21, so that as the cramping head is advanced the pawl 27 holds the gear segment 20 in position.

A pawl releasing bar 30, extends up in a cylindrical head 31 secured to the housing 11, and the rod 30 is secured to one end of a lever bar 32. The lever bar is pivoted at 33 somewhat eccentrically so that a pawl release handle 34 may be depressed and cause the elevation of the pawl 35 releasing bar 30.

The operation of the cramping device will be obvious. The apparatus is moved into position for use with a cramping head 9 arranged with its groove 35 engaging the tongue of the floor board to be cramped into position. The foot treadle 15 is then depressed to a desired extent, the cleats 3 meanwhile holding the apparatus in position. After the floor board has been nailed into position, the pawl release handle 34 is depressed and the cramping head may be released from contact with the flooring board and moved to another position.

Having thus described our invention, what we claim as new and desire to secure by Letters Patent is:

1. In a floor cramp, a supporting frame, a rack bar slidably mounted in said frame and having a cramping head thereon, a gear segment journaled in said frame having gear teeth engaging

- the gear teeth of said rack, an actuating lever pivoted in said frame, a spring tensioned link connected to said lever and to said gear segment eccentric of the journal thereof, and pawl and ratchet means for holding said gear segment in different positions of compression of said spring.
2. In a floor cramp, a supporting frame, a rack bar slidably mounted in said frame and having a cramping head thereon, a gear segment journaled in said frame having gear teeth engaging the gear teeth of said rack, an actuating lever pivoted in said frame, a spring tensioned link connected to said lever and to said gear segment eccentric of the journal thereof, and pawl and ratchet means for holding said gear segment in different positions of compression of said spring, said cramping head swiveled on a vertical pivot in said rack bar.
3. In a floor cramp, a supporting frame, a rack bar slidably mounted in said frame and having a cramping head thereon, a gear segment journaled in said frame having gear teeth engaging the gear teeth of said rack, an actuating lever pivoted in said frame, a spring tensioned link connected to said lever and to said gear segment eccentric of the journal thereof, and pawl and ratchet means for holding said gear segment in different positions of compression of said spring, the slidable mounting for said rack bar comprising a slotted portion extending downwardly at a slight angle to the horizontal.
4. In a floor cramp, a supporting frame, a rack bar slidably mounted in said frame and having a cramping head thereon, a gear segment journaled in said frame having gear teeth engaging the gear teeth of said rack, an actuating lever pivoted in said frame, a spring tensioned link connected to said lever and to said gear segment eccentric of the journal thereof, and pawl and ratchet means for holding said gear segment in different positions of compression of said spring, and cleats adjustably mounted in said supporting frame.
5. In a floor cramp, a slidable rack bar, a gear segment for actuating said rack bar and an actuating lever having a link connected to said gear segment and eccentric of the journal of said gear segment, and means for holding said gear segment in different positions of compression of said spring, and cleats adjustably mounted in said supporting frame.
6. In a floor cramp, a slidable rack bar, a gear segment for actuating said rack bar and an actuating lever having a link connected to said gear segment and eccentric of the journal of said gear segment, a compression spring connected to said link and pawl and ratchet means for holding said gear segment in advanced positions of movement.
7. In a floor cramp, a slidable rack bar, a gear segment for actuating said rack bar and an actuating lever having a link connected to said gear segment and eccentric of the journal of said gear segment, a compression spring connected to said link and pawl and ratchet means for holding said gear segment in advanced positions of movement, and means for releasing said pawl to permit said spring to retract said gear segment.
